(57) **CLAIM**

The ornamental design for a bluetooth low energy beacon, as shown and described.

DESCRIPTION

FIG. 1 is a perspective top view of a bluetooth low energy beacon showing our new design;

FIG. 2 is perspective bottom view thereof;

FIG. 3 is a top view thereof;

FIG. 4 is a front end view thereof;

FIG. 5 is a back end view thereof;

FIG. 6 is a bottom view thereof;

FIG. 7 is a side view thereof; and,

FIG. 8 is another side view thereof.

In the drawings, the broken lines depict environmental subject matter only and form no part of the claimed design.
